Application July 2, 1947, Serial No. 758,675

7 Claims. (Cl. 299—58)

1

My invention relates to a remotely adjustable valve system for discharging a stream of fluid into one or more tanks or containers under controlled conditions. It finds particular utility in those arts in which it is desired to discharge a stream of liquid into a space, e. g., the interior of a tank, in a carefully controlled manner.

It is often desirable to discharge such a stream while adjustably controlling the amount of fluid discharged, the velocity of the discharged stream, the "throw" of the stream, the size of the stream, the degree of agitation or mixing during discharge, or the degree of circulation induced in the medium in the tank by the incoming stream. It is an object of the present invention to provide a novel valve system or fluid distribution system in which one or more of such factors can be controlled or adjusted.

The invention is particularly concerned with the discharge of liquids, but such liquids may be of various composition, depending upon the process in which the invention is used. In some instances, the liquid may be of uniform composition throughout, e. g., a single-phase system. On the other hand, particular advantages arise from use of the invention in the making and separating of composite or multi-phase streams, e. g., dispersions or emulsions of two relatively immiscible liquids, a suspension of solid particles in a liquid phase, a suspension or dispersion comprising a liquid phase carrying either liquid or solid dispersoids, etc. All such multi-phase systems are hereinafter referred to as dispersions.

It is an object of the invention to provide a novel adjustable valve system for such dispersions and adapted, among other things, to control the mixing action exerted on a stream of the dispersion during passage therethrough, whether used alone or in conjunction with other mixing devices; to exert a minutely-adjustable mixing action at the point of delivery of the stream to the processing tank; to reform the interfaces of such a dispersion at the instant of discharge into a tank, etc.

To obtain these and other desirable effects, it is desirable to use a distributor or valve system providing a discharge opening and a movable discharge-controlling member arranged to define an orifice through which the fluid discharges, the discharge-controlling member being biased toward orifice-closing position. It is an object of the present invention to provide a novel torsion means for biasing such a movable discharge-controlling member and to provide a novel adjustment therefor, the torsion means comprising a relatively long spring torsion member.

It is a further object of the invention to connect operatively one end of a spring torsion member and a discharge-controlling member in such manner as to exert a pull on the latter member as determined by the torsional force in the spring torsion member, and to twist another portion

of the spring torsion member to establish a torque in the torsion member.

Another object is to provide a variable area discharge orifice at the end of a pipe, and to change the size of this orifice by twisting a spring torsion member extending into a portion of the pipe.

Still another object of the invention is to extend such a spring torsion member to an operative position outside the tank for application and adjustment of torsion.

Another object is to provide for the periodic flushing or cleaning of the fluid-conducting system, including the discharge orifice, and for subsequent reapplication of the identical biasing force previously applied.

Other objects and advantages of the invention will be evident to those skilled in the art from the following description of exemplified embodiments.

Referring to the drawings:

Fig. 1 is a diagrammatic view showing the application of the invention to the distribution of fluid to a plurality of tanks;

25 Fig. 2 is a view, partially in section, of one embodiment of the fluid distribution system or valve system;

Fig. 3 is a fragmentary sectional view taken on the line 3—3 of Fig. 2;

30 Fig. 4 is an end view partially in section taken on the line 4—4 of Fig. 2;

Fig. 5 is a sectional view taken along the irregular line 5—5 of Fig. 4;

35 Fig. 6 is an end view of an alternative control means of the invention; and

Fig. 7 is an elevational view of the control means of Fig. 6, taken as indicated by the arrow 7.

The invention will be exemplified with reference to the synthesizing and separation of dispersions or emulsions, the separation being aided, if desired, by various treating expedients applied either ahead of or within the tanks.

As shown in Fig. 1, a pump 10 forces a stream 45 of one of the liquids, e. g., mineral oil, along a pipe 11 to a junction 13 where it is met by a stream of the other liquid, e. g., a liquid capable of reacting chemically or combining physically with certain undesired constituents of the first

50 stream, while being sufficiently immiscible therewith to form a dispersion. This other stream reaches the junction 13 through a pipe 14 under the action of a pump 15. In a typical installation, water can thus be introduced into certain

55 oils to remove water-soluble materials which can be brought into association with the water by mere mixing or by supplementary processing steps within the tanks to be described. A dispersion of the two liquids is produced when the streams are first brought together at the junction 13, during flow along a pipe 16, during flow through a weight-loaded mixing valve 17, and/or 60 at the point of discharge into the tank.

In some processes, it is desirable to add chemical treating agents or modifying agents to one or the other or both of the two streams before formation of the dispersion or even after it is formed. In this connection, Fig. 1 shows pipes 22 and 23 through which such materials can be introduced into the pipe 11, either ahead of or beyond the pump 10. Pipes 24 and 25 can be used to introduce such materials at the intake or discharge of the pump 15. Pipe 26 may be used to discharge such material into the dispersion flowing in the pipe 16.

The dispersion-synthesizing means thus far described is employed with one or more tanks, two of such tanks 30 and 30' being shown in Fig. 1, the stream of the dispersion dividing at a junction 32 and moving under pressure to the respective tanks through pipes 33 and 33'. Flow meters M and M' may be disposed in these pipes. As the tanks 30 and 30' and their related equipment are identical, a specific description of the valve system or fluid distribution system for one tank will suffice.

The valve system for each tank is best shown in Fig. 2, which exemplifies the invention with reference to discharge of a horizontal stream of the dispersion into the tank. In the illustrated embodiment, the dispersion is delivered radially outward from a discharge position coaxial with the vertical axis of the tank and at a vertical position which will be determined by the processing steps employed in the particular system. It is usually desirable that the stream be discharged into the tank in submerged position so as to be jetted outwardly in a liquid environment.

As best shown in Figs. 1 and 2, the valve system includes a first pipe means which may include that portion of the pipe 33 which extends into the tank 30 and a first or riser pipe 34. In the preferred construction, a four-way pipe fitting or junction member 35 is used, the end of the pipe 33 being threaded into one of the horizontal legs and the lower end of the riser pipe 34 being threaded into the upper vertical leg, the lower vertical leg being closed by a plug 36. The riser pipe 34 provides a fluid-conducting passage 38 receiving fluid under pressure from a chamber 39 of the junction member 35. For a purpose to be later described, the remaining horizontal leg of the junction member 35 preferably receives a second pipe 40 providing a passage 41 which opens on the chamber 39.

The incoming fluid or dispersion flowing through the pipe 33 under the action of the pumps 10 and 15, or any other pressure means, moves upwardly in the riser pipe 34 as indicated by the arrows 42. The riser pipe is shown as including a T-fitting 44 and a stationary discharge member 45, the latter providing a discharge opening 46 ending at a seat 47 which is shown as an annular wall extending substantially horizontally. Positioned in the path of flow of the fluid is a discharge-controlling member 50 movable with respect to the discharge member 45 to provide a variable-area discharge orifice 51 through which discharges a radially-flowing stream 52 which is jetted horizontally from all peripheral portions of the discharge orifice 51. The desired degree of vertical flaring of this stream, if any, is determined by the design of the valve system, particularly the shape of the seat 47 and a cooperating annular wall 47a of the movable discharge-controlling member 50.

The discharge-controlling member 50 is preferably biased toward closed-orifice position by a biasing means to be later described. In the preferred embodiment of the invention, the discharge-controlling member 50 is positioned to be urged toward orifice-opening position by fluid under pressure in the riser pipe 34. In the illustrated embodiment, this is accomplished by forming the member 50 as a head extending across the upper end of the discharge opening 46 of the discharge member 45 so that fluid under pressure therein will exert on the discharge-controlling member 50 an upward force tending to lift same against the biasing force and toward open-orifice position to increase the thickness of the stream 52. In the absence of this flow of fluid, the movable discharge-controlling member 50 will be resiliently seated on the seat 47 in closed-orifice position. To obtain a better control of the mixing action and a better centering action, the lower surface of the discharge-controlling member 50 may be curved to form a point-like extension 53 which spreads the stream toward the discharge orifice 51.

The downward resilient biasing force on the discharge-controlling member 50 is preferably exerted through an actuating member or tension member generally indicated by the numeral 55 extending longitudinally of the first or riser pipe 34. The uppermost end of such a tension member is operatively connected to the discharge-controlling member 50 and is shown as comprising an upper member 56 extending through and secured to the member 50. Spiders 58 may be secured to the upper member 56 to guide the discharge-controlling member 50 in its vertical movement and to center the upper member 56. The tension member 55 also includes a lower member 60, the adjacent ends of the members 56 and 60 being differentially or oppositely threaded to extend into a correspondingly-threaded sleeve 61 adjacent the T-fitting 44. Removal of a plug 62 in this T-fitting gives access to the sleeve 61 which, by being rotated in one direction or the other, serves to adjust the total length of the tension member 55. Once adjusted, a suitable locking means, such as cotter pins 63, serves to lock the assembly.

A resilient downward pull is exerted on the lower end of the tension member 55 by a novel torsion means adjustable from a position outside the tank 30. This torsion means preferably includes a relatively long and thin spring torsion member 65, e. g., a spring torsion rod. The spring torsion member 65 is relatively resilient in torsion, as distinct from being a rigid structural member and for this purpose it is preferable that the ratio of its effective length to its diameter should be in excess of about 30:1. It extends from the chamber 39 along the passage 41 of the second pipe 40 to a position outside the tank. As will be later described, the outer end of the torsion member 65 is twisted to establish a torsion throughout the length of this member in a direction tending to turn the inner end of the member about its axis to apply the resilient bias through the tension member 55 to the discharge-controlling member 50.

The inner end of the spring torsion member 65 is operatively connected to the discharge-controlling member 50 through the tension member 55 by a means which translates rotary motion of the inner end of the torsion member into a substantially linear motion, which is transmitted to the lower end of the tension member 55 to exert a

downward pull. The resiliency of the downward biasing force depends primarily upon the torque resiliency of the torsion member 65, aided in part by the longitudinal elasticity of the tension member 55. These two sources of resiliency can be relatively varied by changing the size of the torsion member 65 relative to the tension member 55, but it is usually preferred that a major portion of the resilient action arise from the twist or torque in the torsion member 65.

The preferred way of translating a twist or rotary motion of the inner end of the torsion member 65 into a longitudinal pull on the lower end of the tension member 55 is best shown in Figs. 2 and 3. As there shown, two upper members or bolts 67 extend through the junction member 35 and its chamber 39 in horizontally-aligned relationship. These bolts 67 serve as a restraining means or rail means for preventing upward movement of the inner end of the torsion member. A lower member or bolt 68 traverses the junction member 35 and the chamber 39 at a lower position. The inner end of the torsion member 65 extends between the upper and lower bolts 67 and 68 and its uppermost position is determined by engagement with the lower surfaces of the upper bolts 67, as shown. Similarly, its lowermost position is determined by engagement with the upper surface of the lower bolt 68.

In the preferred embodiment, a linkage is employed to interconnect the torsion member 65 and the tension member 55. As best shown in Fig. 3, this linkage may include a lever 70 welded or otherwise secured to the torsion member 65 at a position below the tension member 55. The end of this lever 70 extends between bifurcations 71 of an attachment member 72, through which the lower member 60 of the tension member 55 extends, this lower member being threaded to receive a nut 73 and carrying a collar 74 above the attachment member 72 to limit the downward movement of the lower member 60. A pin 75 traverses the bifurcations and the lever 70 to connect pivotally the lever to the attachment member 72. A set screw 76 in one or both of the bifurcations retains the pin 75 against axial movement. Correspondingly, any tendency of the inner end of the torsion member 65 to turn in a counter-clockwise direction, as viewed in Fig. 3, will exert a resilient downward pull on the tension member 55.

It will be apparent from Figs. 3 and 5 that the torsion member 65 is displaced to one side of, but extends substantially parallel to, the axis of the passage 41 of the second pipe 40, the displacement being substantially equal to the lever arm of the lever 70. It is desirable that the axis of the torsion member lie along a straight line, thus preventing bends which might cause undue stresses in local sections of the torsion member when the torsion is applied. Rightward movement of the torsion member 65 or of the lower end of the tension member 55, as viewed in Fig. 3, is prevented by engagement of the circular or base portion of the lever 70 with the inside wall of the chamber 39. Leftward movement of the inner ends of the members 55 and 65 can be prevented by any suitable means such as a plate 78 slidably engaged by the sides of the attachment member 72 and its bifurcations 71. As best shown in Figs. 2 and 3, this plate 78 is of a size to fit snugly between the bolts 67 and carries at its lower end a spacing sleeve 79 surrounding the bolt 68 and extending to a side wall of the junction member 35 to retain the plate 78 in

guiding relationship with the attachment member 72.

The second pipe 40 extends to a wall of the tank 30, which acts as a support therefor, and preferably to a position therebeyond. As shown, the main portion of this second pipe 40 comprises a pipe 80 carrying a flange 81. The outer portion of the second pipe 40 is shown as comprising a flanged nipple 82 with its inner flange connected to the flange 81. This flanged nipple 82 is welded or otherwise secured to a wall 83 of the tank 30, this wall 83 being either a portion of the main side wall of the tank or a removable section thereof. In either instance, the wall 83 forms a means for receiving the reaction torque of the spring torsion member, as later explained. A head 84, outside the tank 30, closes the end of the passage 41 formed by the second pipe 40.

A suitable twisting or control means 85, positioned outside the tank 30, is used to apply and maintain a torque in the torsion member 65 and thereby control the downward resilient force applied to the discharge-controlling member 50. The details of one embodiment of the control means are best shown in Figs. 2, 4 and 5. Referring thereto, the torsion member 65 extends through a neck 87 welded to the head 84 and carrying a packing gland or sealing means 89 which guides and journals the torsion member 65 and forms a motion-permitting, fluid-tight seal therefor. That portion of the torsion member 65 beyond the sealing means 89 is journaled in a bracket 90 detachably connected to the head 84 by a bolt 91. Between the journaling portion 35 of the bracket 90 and the sealing means 89 is positioned a lever 92 bifurcated to be clamped by bolts 94 to the outer end of the torsion member 65, the length of the lever 92 being greater than the lever 70.

The control means 85 includes also a means for adjustably moving the lever 92 to establish an adjustable torsional force or twist in the spring torsion member 65. This means is shown as including a tube 96 welded or otherwise secured to the head 84 and carrying a support means 97 removably held in position by a bent pin 98. The support means 97 threadedly receives an engagement member 99, shown as comprising a wing-headed bolt engaging the lever 92. By turning the engagement member to advance through the support means 97, an increasing torque is applied to the torsion member 65 through the lever 92.

The engagement member 99 is preferably disposed substantially in a plane perpendicular to the axis of the outer end of the torsion member 65. It applies to the lever 92 a pressure having a component in this plane and tangential to a circle drawn about the axis of the outer end of the torsion member 65. The engagement member 99 is preferably mounted for disposition in and withdrawal from the locus of motion of the lever 92. In the embodiment heretofore described, this is accomplished by the removable connection of the support means 97 relative to the tube 96 when the bent pin 98 is withdrawn.

An alternative form of twisting or control means is shown in Figs. 6 and 7 in which the support means comprises an adjustable block 101 carrying a conventional bolt acting as the engagement means 99 and bearing against the lever 92 as previously described. The block 101 is adjustably positioned with respect to an arcuate plate 102 mounted in spaced relationship with the head 84, as by short legs 103. The annular plate provides two series of holes disposed in

pairs and bolts 105 extend through any selected pair of holes to retain the support means, comprising the block 101, in any selected position. In this embodiment, a suitable weight can be applied to the end of the lever 92 to establish a torque approximately of the desired value. Thereafter, the block can be bolted in place and additional adjustments can be made by turning of the engagement member 99.

It will be apparent from the foregoing that the valve system or fluid distribution system can be adjusted from a position outside the tank 30 and that this adjustment can be made without interfering with the operation of the equipment. The discharge-controlling member 50 is urged toward open-orifice position by the pumped stream. The downward resilient or biasing pressure applied to this discharge-controlling member can be adjusted by turning the engagement member 99. By increasing the downwardly-acting biasing force, it is possible to control accurately the volume of fluid discharged, the velocity of the stream 52, the "carry" of the stream, the mixing action at the point of discharge or in the discharge orifice 51, the relative amounts of fluid entering the tanks 30 and 30', etc.

As the engagement member 99 is turned to apply a closely-adjustable twist to the torsion member 65, the reaction torque is transmitted through this engagement member to the outer end of the second pipe 40, namely, to the flanged nipple 82 in the illustrated embodiment, to be received by the wall 83 which takes the reaction torque. This is in contradistinction to transmitting this reaction torque through the pipe 80 to be taken by the junction member 35.

An important feature of the invention is that the biasing force can be removed at intervals to permit flushing of the system without draining the tank, after which the apparatus can be re-turned to the previous bias setting without difficulty. In certain processes, it is found that accumulations of foreign matter, such as scale, tend to form in the valve system. These accumulations are particularly harmful adjacent the discharge orifice 51 and it is often found that foreign bodies, such as scale, etc. may accumulate at one or more peripheral positions to interfere with the desired peripherally-continuous, sheet-like discharge. When this occurs, it is desirable to relieve the biasing pressure to flush out the system. With the control means of Figs. 2, 4, 5, 8 and 9, the bent pin 98 can be removed and the support means 97 withdrawn, the setting of the engagement member 99 being retained. This will release the torsion in the spring torsion member 65. The corresponding release in biasing pressure applied to the discharge-controlling member 50 may dislodge any obstruction in the system, although it is usually desirable to decrease or eliminate the supply of fluid and to oscillate the lever 92 to transmit a rapid vibration to the discharge-controlling member 50, causing it to move upwardly and downwardly with respect to the stationary discharge member 45. It will be observed that the invention provides a positive connection between the torsion member and the discharge-controlling member 50 so that the latter may be moved positively relative to the seat 47. This facilitates dislodgement of scale or obstructions, particularly if the discharge-controlling member 50 is rapidly oscillated to apply percussion blows to the discharge member 45.

At the same time, the invention provides a means for re-applying the same biasing force

as was present before the flushing operation. In many instances, the previously-applied biasing force may have been quite critical and it is desirable to re-apply exactly the same force. This is accomplished merely by re-inserting the support means 97 and inserting the bent pin 98, all without disturbing the setting of the engagement member 99. In re-inserting the support means, the lever 92 may be depressed manually or by any suitable means. Upon release of this depressing force, the lever will return to its former position, as determined by contact with the engagement member 99.

Similarly, the control means shown in Figs. 6 and 7 provides for the same flushing action and return of the previous biasing force. In this embodiment, the block 101, comprising the support means, can be detached by loosening the bolts 105. This will release the lever 92 and the system can be flushed or cleaned as previously described. Thereafter, the block 101 can be replaced without disturbing the setting of the engagement member 99, whereby an identical biasing force is re-applied.

If the complete apparatus shown in Fig. 1 is employed for synthesizing and separating dispersions, it will be apparent that the separate streams delivered to the tanks 30 and 30' can be individually adjusted in volume, degree of mixing action upon discharge, etc., by adjustment of the corresponding engagement member 99. For example, if it appears that the processing capacity of one tank is being exceeded, the operator can adjust the biasing force to reduce the flow thereto or change the mixing action at the point of discharge. In some instances, the processing steps may be largely completed before the dispersion enters the tanks, as, for example, by permitting completion of reactions or physical associations before discharge into the tanks. In this instance, the tanks may serve merely as a separating means. On the other hand, processing steps in addition to mere separation may be conveniently performed in the tanks or additional aids to resolution or separation may be utilized within the tanks. Numerous types of such aids are familiar to those skilled in the art, such, for example, as the use or application of heat, pressure, agitation, chemical action, electric fields, etc. within the tank.

Various types of processing steps performed in the tanks can be facilitated by agitation or circulation within the tank induced by the incoming stream. For example, in Fig. 1 the stream 52 may discharge in submerged position to establish recirculation paths within a liquid in the tank. Fig. 1 shows upper and lower annular members 120 and 121 mounted to extend substantially horizontally at positions respectively above and below the elevation of the discharging stream 52. Such members may be perforate or imperforate and may be held in position by any suitable means, not shown. The stream 52 may be discharged in spaced relationship with each of these members and the injector action of the stream will draw liquid into the central openings of the annular members 120 and 121 and establish upper and lower closed circulation therearound, as indicated respectively by arrows 123 and 124.

Such a system may be advantageously employed to prolong the time of contact between chemical materials and the constituents of the stream 52. It may also be employed advantageously to discharge the incoming stream into a body of washing liquid. If the incoming stream

comprises oil, washing through a body of water is often desirable and the upper surface of this water may be carried above the discharge-controlling member 50, e. g., as indicated by the numeral 125. In such instances, the washed oil can be removed through an upper pipe 126 to a header 127, suitably valved at 128 to maintain a back pressure on the tank, while the washing or other liquid can be withdrawn from the lower end of the tank through a pipe 129 to move to a header 130, also suitably valved at 131 for a similar purpose. If both tanks are being employed, the upper effluent from the tank 30' is preferably moved to the header 127 ahead of the valve 128 through a pipe 126', the lower effluent being similarly delivered to the header 130 ahead of the valve 131 through a pipe 129'. Control of back pressures by throttling the effluent flows in the headers produces advantageous results as compared with individually throttling the flows from the individual tanks. In this connection, the upper effluents of the two tanks are always at the same pressure, as are also the lower effluents of these tanks, and the relative amounts of liquids delivered to the two tanks are directly determined by the relative settings of the two control means.

On the other hand, if the interfacial level is carried below the discharge-controlling member 50, for example, at a level indicated at 139, the incoming stream will be discharged into the upper of two separated, or partially separated, bodies and the induced recirculation indicated by the arrows 123 and 124 may aid in the treatment being carried out within the tank 30. For example, the recirculations may retain or carry any material not completely processed until this processing is complete, at which time the material can separate from the recirculation paths. In other instances, the induced recirculations can be very advantageously used if some treating action takes place between the annular members 120 and 121, for example, if these members are maintained at a different potential to establish therebetween a cataphoretic or coalescing electric field.

While the invention has been particularly exemplified with reference to the synthesizing and separation of dispersions, it should be clear that the apparatus may be used in the processing of various homogeneous liquids without departing from the spirit of the invention. In this event, the pump 10 may deliver the homogeneous liquid to the system and the pump 15 may deliver another liquid miscible therewith. This second liquid may be of such character as to throw down precipitates which settle in the tanks, or it may be of such nature as to partially complete its action before discharge through the orifice 51 and partially after discharge into the liquid body in the tank. If the process is one which produces precipitates, these can be separated in the tank and withdrawn through the pipe 130 or they may remain in the main stream of liquid to discharge through the pipe 127.

This application is a continuation-in-part of my application Serial No. 483,661, filed April 19, 1943, now Patent No. 2,443,646, issued on June 22, 1948.

Various changes and modifications can be made without departing from the spirit of the invention as defined in the appended claims.

I claim as my invention:

1. In an apparatus for placing an adjustable tension in a tension member having a tension-applying end and a remote end, said tension

member extending inside a first pipe means having a remote end adjacent said remote end of said tension member and pressurally coupled therewith to impose a compressive force on said first pipe means when said tension-applying end is pulled to establish a tension therein, there being a fluid conductive space inside said first pipe means around said tension member, said apparatus including in combination: a second pipe means extending substantially at right angles from said first pipe means; a hollow junction member rigidly connected to said second pipe means and providing means for connecting said first pipe means rigidly thereto, said junction member joining said first and second pipe means, the interior of said second pipe means communicating with the interior of said first pipe means through said junction member; an end member on that end of said second pipe means removed from said junction member; a spring torsion rod extending longitudinally completely through said second pipe means and having an inner end in said junction member and an outer end rotatably extending through said end member to a position outside said second pipe means; means traversing the interior of said hollow junction member and engaging said inner end of said spring torsion rod to restrain same from movement in a direction axially of said first pipe means; a linkage in said hollow junction member for operatively connecting said inner end of said spring torsion rod to said tension-applying end of said tension member to exert a pull on the latter when said outer end of said spring torsion rod is turned axially in one rotative direction to thereby place a tension stress in said tension member and a compressive stress in said first pipe means; and means for twisting said outer end of said spring torsion rod at a position outside said second pipe means to turn same through a sufficient angle in said one rotative direction to place said rod under torsion, said twisting means including means for holding said outer end of said spring torsion rod in its twisted position to maintain it in torsion and place said tension member under tension and said first pipe means under compression.

2. In an apparatus for placing an adjustable tension in a tension member having a tension-applying end and a remote end restrained against movement axially of said tension member to permit establishing a tension therein when said tension-applying end is pulled, said apparatus including in combination: a pipe means extending substantially at right angles to said tension member from one side thereof and having a closed outer end; a spring torsion rod within said pipe means and having an axis extending substantially at right angles to the axis of said tension member, said spring torsion rod having an inner end near said tension-applying end of said tension member and having an outer end extending rotatably from said closed end of said pipe means to a position outside said pipe means; a linkage for operatively connecting said inner end of said spring torsion rod to said tension-applying end of said tension member to exert a pull thereon when said outer end of said spring torsion rod is turned axially in one rotative direction; a hollow junction member into which extends said tension-applying end of said tension member and said inner end of said spring torsion rod, said pipe means being secured to said hollow junction member, said linkage being disposed within said hollow junction member;

means inside said hollow junction member for restraining said inner end of said spring torsion rod against movement in a direction axially of said tension member; and means outside said pipe means for twisting said outer end of said spring torsion rod to turn same in said one rotative direction and through a sufficient angle to place said rod under torsion and apply a tension force to said tension member by pulling thereon, said twisting means including means for holding said outer end of said spring torsion rod in its twisted position to maintain it in torsion.

3. In an apparatus for placing an adjustable tension in a tension member having a tension-applying end and a remote end restrained against movement axially of said tension member to permit establishing a tension therein when said tension-applying end is pulled, said apparatus including in combination: a pipe means extending substantially at right angles to said tension member from one side thereof and having a closed outer end; a spring torsion rod within said pipe means and having an axis extending substantially at right angles to the axis of said tension member, said spring torsion rod having an inner end near said tension-applying end of said tension member and having an outer end extending rotatably from said closed end of said pipe means to a position outside said pipe means; a linkage for operatively connecting said inner end of said spring torsion rod to said tension-applying end of said tension member to exert a pull thereon when said outer end of said spring torsion rod is turned axially in one rotative direction; means outside said pipe means for twisting said outer end of said spring torsion rod to turn same in said one rotative direction and through a sufficient angle to place said rod under torsion and apply a tension force to said tension member by pulling thereon, said twisting means including means for holding said outer end of said spring torsion rod in its twisted position to maintain it in torsion; and a support for said pipe means intermediate the ends thereof whereby said pipe means includes an outer section extending beyond said support, said twisting means including means acting between said outer end of said spring torsion rod and said outer section of said pipe means, said outer section of said pipe means thus receiving the reaction force of said twisting means and tending to be twisted in a reverse direction as compared with said spring torsion rod, the reaction force being transmitted through said outer section of said pipe means to said support.

4. In an apparatus for placing an adjustable tension in a tension member having a tension-applying end and a remote end restrained against movement axially of said tension member to permit establishing a tension therein when said tension-applying end is pulled, said apparatus including in combination: a pipe means extending substantially at right angles to said tension member from one side thereof; a member for closing the outer end of said pipe means, said member having an opening communicating with the interior of said pipe means at a position to one side of the axis thereof; a spring torsion rod within said pipe means and having an axis substantially at right angles to the axis of said tension member, said spring torsion rod having an inner end near said tension-applying end of said tension member and having an outer end extending rotatably from said pipe means through said opening

of said member and to a position outside said pipe means, said torsion rod extending off center along said pipe means on one side of the central axis of said pipe means; a linkage for operatively connecting said inner end of said spring torsion rod to said tension-applying end of said tension member to exert a pull thereon when said outer end of said spring torsion rod is turned axially in one rotative direction; and means outside said pipe means for twisting said outer end of said spring torsion rod to turn same in said one rotative direction and through a sufficient angle to place said rod under torsion and apply a tension force to said tension member by pulling thereon, said twisting means including means for holding said outer end of said spring torsion rod in its twisted position to maintain it in torsion.

5. An apparatus as defined in claim 4 in which said linkage includes a lever secured to the inner end of the off-center spring torsion rod and extending in a direction toward the axis of said pipe means to provide an inner end, and means for connecting said inner end of said lever to said tension-applying end of said tension member.

25 6. In an apparatus for placing an adjustable tension in a tension member having a tension-applying end and a remote end restrained against movement axially of said tension member to permit establishing a tension therein when said tension-applying end is pulled, said apparatus including in combination: a spring torsion rod having an axis extending substantially at right angles to the axis of said tension member, said spring torsion rod having an inner end near said tension-applying end of said tension member and an outer end at a remote point; means for operatively connecting said inner end of said spring torsion rod to said tension-applying end of said tension member to exert a pull thereon when said spring torsion rod is turned axially in one rotative direction; a head member at said remote point, said outer end of said spring torsion rod extending beyond said head member; a lever secured to said outer end of said spring torsion rod at a position beyond said head member; walls secured to said head member to provide a socket; a support means removably retained in said socket; and an engagement member threadedly received by said support means and bearing against said lever to adjustably twist said outer end of said spring torsion rod, the torsion in said rod being temporarily removable and exactly replaceable by removing said support means from said socket while the setting of said engagement member relative to said support means remains unchanged.

30 7. An apparatus as defined in claim 6, in which said wall means provides a plurality of sockets selectively receptive of said support means.

Certificate of Correction

Patent No. 2,557,847

June 19, 1951

DELBER W. TURNER

It is hereby certified that error appears in the above numbered patent requiring correction as follows:

In the grant, line 6, title of invention, for "STEMS" read *SYSTEMS*; and in the heading to the drawings, sheets 1 and 2, line 2, and in the heading to the printed specification, line 2, for "STEM" read *SYSTEM*; column 10, line 46, for "tenson" read *tension*; column 11, line 31, for "tenison-applying" read *tension-applying*;

and that the said Letters Patent should be read as corrected above, so that the same may conform to the record of the case in the Patent Office.

Signed and sealed this 11th day of September, A. D. 1951.
